MUSCLE TONE STIMULATION DEVICE

Milton E. Foster, Palos Verdes Peninsula, Calif., assignor
to Techni Med Inc., Torrance, Calif.

Filed Nov. 24, 1972, Ser. No. 309,252

Term of patent 14 years

Int. Cl. D28—03

U.S. Cl. D83—1 T

FIG. 1 is a view in perspective of the front and right side of a muscle tone stimulation device showing my new design;

FIG. 2 is a top plan view thereof;

FIG. 3 is a rear view thereof;

FIG. 4 is a view of the left side thereof; and

FIG. 5 is a bottom view thereof.

I claim:

The ornamental design for a muscle tone stimulation device, as shown.
